UNITED STATES PATENT OFFICE.

GEORGE HILLARD BENJAMIN, OF NEW YORK, N. Y.

METHOD OF DEHYDRATING AND CURING TOBACCO.

1,224,703.

Specification of Letters Patent.

Patented May 1, 1917.

No Drawing.

Application filed September 23, 1914. Serial No. 863,100.

To all whom it may concern:

Be it known that I, GEORGE HILLARD BENJAMIN, a citizen of the United States, residing at New York city, in the county and State of New York, have invented a new and Improved Method of Dehydrating and Curing Tobacco, of which the following is a specification.

My improved method has for its objects; 10 first, to remove the major portion of the normally contained moisture in the tobacco, and second, to develop the color and aromatic properties of the tobacco.

To carry my invention into effect, I proceed in the following manner:

The tobacco leaves as taken from the fields, are suspended in a dehydrating or curing apparatus of any suitable description, such for instance as is described in my prior 20 application, Serial No. 854,598 filed August 1st, 1914, and therein subjected, first to the action of large volumes of heated air (preferably dry air) until the moisture contents of the tobacco have been reduced to a definite 25 amount *i. e.*, to such an amount as will maintain the cell membranes of the tobacco cells in a condition to permit endosmosis of water should the tobacco be immersed in water at some subsequent period, but insufficient to 30 coact with the enzym carried by the tobacco to produce fermentation or mold when stored; and second, to the action of a temperature sufficient to develop the color and aromatic properties of the tobacco without 35 changing the water contents, rupturing the cell walls, materially altering the chemical characteristics, or producing any considerable volatilization of the ingredients of the tobacco.

40 In practice, I prefer to subject the tobacco to the action of moving currents of air of large volume, from which the major portion of the moisture has been removed and heated to approximately 110° Fahrenheit. The 45 action of the air currents should be maintained for anywhere from one to three hours, depending somewhat upon the nature of the tobacco treated.

Tobacco, as is well known, varies as to the 50 character of the leaf, that is, its texture, amount of water, nicotin, essential oils, acids, etc. With leaves of coarse texture, which, to use a trade term, sweat easily, the time of treatment at the temperature stated 55 may be reduced, whereas with leaves of

close texture, it may be extended, from which it will be understood that the exact length of time of treatment is dependent upon conditions of the leaf, temperature of the external air, etc.

After the treatment at the temperature stated has been continued for the required time, that is, for sufficient length of time to take out all water which is easily exuded by exosmotic action, the temperature is raised to between 120-140° Fahrenheit, and continued for from two to five hours, depending upon the condition of the leaf. Subsequently the temperature is again raised to between 140-160° Fahrenheit, or as has previously been stated, until the leaf contains only such an amount of its original moisture as will permit endosmotic action with water, but not permit or give rise to fermentation or mold in connection with the 75 enzym present.

It will be seen from the above statement, that the method, as far as described, differs radically from the usual method of drying and curing tobacco, in that, while in applicant's method the enzymes are not used in connection with the water present to create fermentation, in the old methods they are. After the tobacco has been dried to the extent stated, the temperature to which it is subjected is increased. This temperature may be applied through the instrumentality of still or moving bodies of air having a temperature of between 200-225° Fahrenheit, which temperature may be continued for anywhere from two to ten hours, depending upon the character of the tobacco and the color and flavor which it is desired the tobacco shall have. The action of the high temperature, effects a change in the essential oils, or otherwise the aromatic ketones, with the effect that the leaf progressively takes a darker shade as the temperature is continued, and becomes more fragrant. In practice I have found that if the leaf is subjected simultaneously to the high temperature stated, and also to rays emitted from an electric light (preferably an arc light, although incandescent lights may be employed) the conversion of the essential oils and color is more rapid than is the case where the high temperature alone is used.

In treating very low grade leaves, I have found it advantageous to combine the old 110

method of operation with that heretofore described, in so far, that the leaf is first air dried by hanging it in an ordinary drying shed and permitting the enzymes present to set up a partial fermentation, at which time the leaf is introduced into the drying apparatus and treated as above described.

Among the advantages of the process set forth above as first and second described, 10 is found: When the dried leaf is exposed to the humid atmosphere, it will readily absorb, by endosmotic action, a certain amount of water, with the result that the leaf is 15 pliable and may be handled without breaking; whereas, in the old method of treatment, while the leaf will condense upon its surface a certain amount of moisture, it will not endosmotically absorb water within the cell walls, and breaks easily. 20 In this specification I have used the word dehydration, and I wish it understood that I understand dehydration as differentiated from desiccation, by the following facts: Dehydration exosmotically draws a definite 25 amount of moisture, depending upon the temperature and length of time of treatment to which the body is subjected, from within the cells of the body acted upon, without rupturing the cell walls or materially 30 altering the chemical characteristics of the body or drying the cell walls to such an extent as to prevent subsequent endosmosis of an external fluid inward through the cell walls, whereas desiccation completely 35 dries the body treated, removing all moisture, destroying the cell structure and putting the body into a condition where subsequent endosmosis is not possible.

In determining the amount of water to 40 be originally taken from the leaf, it is advisable to also determine the amount of water which the leaf will reabsorb from the atmosphere after the process is completed, in order that the total amount of water in 45 the leaf, before storage, shall be less than the theoretical amount (usually about 20% of the original moisture) necessary to coact with the enzym present to set up secondary fermentation or the production of 50 mold.

I wish it understood that I do not limit myself in any wise to the specific temperatures or the length of time of applying the specific temperatures herein set forth, as 55 these factors will, as before stated, depend very largely upon the character of the leaf to be treated.

I have not attempted, in this specification, to explain the effects of the high temperatures. It appears probable, however, 60 that the essential oils present combine in some manner with the acids, and thereby develop the aromatic ketones which are darker in color than the original elements, 65 and so give deeper shades to the leaf as the

treatment progresses. The chemistry of the subject is so little developed, that it is quite out of the question to make any more definite statement.

Having thus described my invention, I claim:

1. The method of dehydrating and curing tobacco, which consists in subjecting the tobacco to the action of large volumes of highly heated dry air, continued until the 75 moisture content of the tobacco is reduced to such an extent as will maintain the cell membrane of the tobacco in a condition to permit endosmosis with water, but insufficient without additional moisture, to coact 80 with the enzym of the tobacco to produce fermentation or mold, and simultaneously subjecting the tobacco to the action of the rays of an electric light of sufficient intensity to affect bodies carried by the leaf and develop the color of the leaf and the aromatic 85 properties of such bodies.

2. The method of dehydrating and curing tobacco, which consists in first subjecting the tobacco to the action of large volumes of highly heated dry air until the moisture content of the tobacco is reduced to such an extent as will maintain the cell membrane in a condition to permit endosmosis with water, but insufficient to coact 90 with the enzym of the tobacco to produce fermentation or mold, and then subjecting the tobacco to a temperature sufficient to develop the aromatic characteristics of the essential oils of the tobacco and to progressively 95 change the color of the tobacco.

3. The method of dehydrating and curing tobacco, which consists in first subjecting the tobacco to the action of large volumes of highly heated dry air until the moisture 105 content of the tobacco is reduced to such an extent as will maintain the cell membrane in a condition to permit endosmosis with water, but insufficient to coact with the enzym of the tobacco to produce fermentation or mold, and simultaneously subjecting the tobacco to the action of electric light and a temperature sufficient to develop the aromatic characteristics of the essential oils 110 of the tobacco and to progressively change the color of the tobacco.

4. The method of dehydrating and curing tobacco, which consists in first subjecting the tobacco to the action of large volumes of dry air heated originally to approximately 110° temperature, and then successively increasing the temperature until the moisture content of the tobacco is reduced to such an extent as will maintain the cell membrane in a condition to permit 120 endosmosis with water, but insufficient to coact with the enzym of the tobacco to produce fermentation or mold, then subjecting the tobacco to approximately 200° temperature to develop the aromatic character- 125 130

istics of the essential oils of the tobacco and to progressively change the color of the tobacco.

5. The method of dehydrating and curing tobacco, which consists in first subjecting the tobacco to the action of approximately 110° temperature and maintaining said temperature for from one to two hours; then raising the temperature to approximately 10 120° and continuing said temperature for from two to five hours; then raising the temperature to approximately 140° and continuing said temperature until such time as the original moisture content of the tobacco 15 is so diminished as to permit endosmotic action through the cell membrane but insufficient to coact with the enzym of the tobacco to produce fermentation or mold, then subjecting the tobacco to approximately 20 200° temperature and continuing said temperature for from two to ten hours, depending upon the character of the tobacco, color and flavor desired, to develop the aromatic characteristics of the essential oils 25 of the tobacco and to progressively change the color of the tobacco.

6. The method of dehydrating and curing tobacco, which consists in first effecting

a partial fermentation of the tobacco by means of the water and enzymes present, 30 then subjecting the tobacco to the action of large volumes of highly heated dry air until fermentation is stopped and the moisture content of the tobacco reduced to such an extent as will maintain the cell membrane 35 in a condition to permit endosmosis with water, but insufficient to coact with the enzym of the tobacco to produce fermentation or mold, and then subjecting the tobacco to a temperature sufficient to develop 40 the aromatic characteristics of the essential oils of the tobacco and to progressively change the color of the tobacco.

7. A step in the method of dehydrating and curing tobacco, which consists in subjecting the tobacco to the action of electric light during the time the tobacco is undergoing dehydration and conversion of its essential oils and color changes.

In testimony whereof, I affix my signature 45 in the presence of two witnesses.

GEORGE HILLARD BENJAMIN.

Witnesses:

HELEN E. KOELSCH,
LESTER BEARDSLEY.

DISCLAIMER

1,224,703.—*George Hillard Benjamin*, New York, N. Y. METHOD OF DEHYDRATING AND CURING TOBACCO. Patent dated May 1, 1917. Disclaimer filed May 4, 1932, by the assignee, *Consumers Tobacco Company*.

Hereby enters this disclaimer by cancelling from the specification at page 1, lines 103 and 104, the words "light (preferably an"; and by further cancelling at lines 104 and 105, the words "although incandescent lights may be employed)," and by disclaiming as to each of claims 3 and 7, subjecting the tobacco to the action of any kind of electric light except electric arc light.
